UNITED STATES PATENT OFFICE.

ORLANDO M. FEE, OF LAMANDA PARK, CALIFORNIA.

COMBINATION GRAVITY LATCH AND LOCK FOR DOORS, WINDOWS, AND GATES.

Application filed January 10, 1924. Serial No. 685,452.

To all whom it may concern:

Be it known that I, ORLANDO M. FEE, a citizen of the United States, residing at Lamanda Park, in the county of Los Angeles and State of California, have invented Combination Gravity Latches and Locks for Doors, Windows, and Gates; and I do hereby declare the following to be a full, clear, and exact description of the invention, such as will enable others skilled in the art to which it appertains to make and use the same.

The invention has relation to fastening means and has for its primary object to provide a device adapted for general use either as a holder or lock, whereby to secure a part such as a window sash in the required adjusted position or to lock the parts, such as a door, sash, gate or the like when closed.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to provided they fall within the spirit and scope of the invention.

Referring to the accompanying drawings forming a part of the application:

Figure 1 is a vertical transverse section of a window provided with fastening means embodying the invention.

Figure 2 is an enlarged sectional view on the line 2—2 of Figure 1.

Figure 3 is a sectional view on the line 3—3 of Figure 2.

Figure 4 is a horizontal sectional view on the line 4—4 of Figure 2.

Figure 5 is a fragmentary elevational view.

Figure 6 is an enlarged sectional view on the line 6—6 of Figure 1.

Figure 7 is a sectional plan view on the line 7—7 of Figure 6.

Figure 8 is a detail perspective view of the fastener.

Figure 9 is an elevational view showing the application of the invention to a door.

Figure 10 is a sectional view on the line 10—10 of Figure 9.

Figure 11 is a plan sectional view on the line 11—11 of Figure 9, and

Figure 12 is a sectional view taken on the horizontal plane indicated by the line 12—12 of Figure 9.

Corresponding and like parts are referred to in the following description and designated in the several views of the drawings by like reference characters.

In its simplest form, the fastener comprises an elongated block 1 provided with a longitudinal slot 2 and end openings for receiving screws or other fastening means whereby to attach the device to the cooperating part. An L-shaped latch 3 is pivoted by one of its members to the block 1, the other member being weighted and normally occupying a position at one side of the block and holding an end of the pivoted member projected so as to engage the part to be held in a predetermined position. In practice the block 1 is let into the part to which it is fitted, as shown most clearly in Figures 6 and 7. When applied to a window, it is preferred to apply a number of the fastenings to the window frame or sash as found most convenient. The numeral 4 designates the sash of a window and 5 the frame or casing. Keepers 6 are shown applied to an upright of the frame to coat with the projecting end of the latch 3 applied to a side stile of the sash 4. By providing a number of keepers 6, as indicated most clearly in Figure 1, the sash may be held at any predetermined position. A flexible connection 7 may be attached to the weighted member of the latch and serves as convenient means for moving the same from the position shown by full lines in Figure 6 to the position shown by dotted lines in the same figure. As indicated in Figure 6, a channel 8 may be formed in a stile of the sash to receive the projecting end of the latch 3, thereby admitting of the sash having a limited movement for ventilation, but preventing anyone entering the window from the outside.

The latch 3 may be held in either extreme adjusted position by means of a dog 9 which is similar in formation to the latch 3 and which is pivoted by one of its members, the other member being weighted to normally hold the dog in a given position. The dog 9 is disposed in a plane at a right angle to the plane of the latch 3 and its pivoted member is adapted to engage the weighted member of the latch whereby to hold the latter in

either position shown by the full and dotted lines in Figure 2. The latch 3 is held in locking engagement by means of the dog 9 engaging the outer edge of the weighted member of the latch, as shown most clearly in Figures 2 and 4. When the latch 3 is moved so as to withdraw the projecting end of the pivoted member, it is retained in such position by the dog 9 engaging the inner edge of its weighted member, as indicated most clearly by the dotted lines in Figure 2. In this position of the parts, the sash or other part may be moved freely in either direction. The dog 9 is adapted to be conveniently operated by means of a flexible connection 7, such as a cord or chain.

In Figures 9, 10 and 11, the fastening is shown applied to a door. The numeral 11 designates the door jamb and 12 the door. The fastening is shown applied to the jamb 11 and coacts with a keeper 13 applied to the door. The latch is adapted to be held in withdrawn position by means of a pin 14 which is introduced into an opening formed in the jamb 11, the projecting end engaging under the weighted member of the latch. When the pin is withdrawn the latch assumes a normal position and engages the keeper 13, thereby locking the door. In this case, the flexible connection 14 is attached to a weight 16 which is suspended upon a pin 17. A yoke 18 is slipped upon the pin 17 in the rear of the weight 16 and a bail 19 attached to the ends of the yoke 18 is connected at one end to the bail and at its opposite end to the door frame to prevent loss or misplacement of the parts. A flexible connection 21, such as a cord, is attached at one end to the bail 19 and its opposite end is made fast to a time-controlled pulley 22 upon which it is adapted to be wound whereby to disengage the weight 16 from the pin 17, the falling of the weight operating to withdraw the latch 3 from locking engagement with the door which, being released, may be opened from the outside. The pulley 22 may be controlled by any preferred type of trap movement 23 which is adapted

to be set so as to release the pulley operating mechanism to effect rotation of the pulley to wind the cord 21 thereon and effect disengagement of the weight 16 from the supporting pin 17. It will thus be understood that prior to leaving an abode, the pin 14 may be placed in position to hold the latch 3 in withdrawn position so that the door 12 may be closed, after which the pin 14 is withdrawn thereby permitting the latch 3 to assume a locking position to secure the door from being opened from the outside. The weight 16 having been suspended from the pin 17 and the connection 21 unwound from the pulley 22 and the clock movement 23 set to release the pulley operating mechanism at the required time, it will be understood that at the time set, the pulley operating mechanism is tripped and the pulley 22 rotated to wind the connection 21 thereon with the result that the weight 16 is disengaged from its supporting pin 17 and falling withdraws the latch 3 from locking engagement with the door which may be opened from the outside, as will be readily understood. This time lock can also be operated by an alarm clock, with a lever arrangement for removing the weight from the pin, with the same results following as above stated, but the lever arrangement is more desirable, as it adds additional power, and is simple and easy to construct.

What is claimed is:

A fastening comprising a longitudinally slotted block, an L-shaped latch pivoted by one of its members within the slot of the block and having its other member weighted and extending below the slot of the block to normally operate so that its distal end portion will engage the block to hold the latch in operative position, and an L-shaped dog pivoted by one of its members and adapted to cooperate with the latch at different locations to selectively hold the latter in locking or withdrawn position.

In testimony whereof I affix my signature.

ORLANDO M. FEE.
